UNITED STATES PATENT OFFICE.

JAMES E. HANGER, JR., OF WASHINGTON, DISTRICT OF COLUMBIA.

GARMENT-SUPPORTER.

1,254,498.

Specification of Letters Patent. Patented Jan. 22, 1918.

Application filed June 5, 1917. Serial No. 172,023.

To all whom it may concern:

Be it known that I, JAMES E. HANGER, Jr., a citizen of the United States, residing at Washington, in the District of Columbia, have invented certain new and useful Improvements in Garment-Supporters, of which the following is a specification.

My invention relates to garment supporters and pertains more particularly to hose supporters.

The object of my invention is to produce a hose supporter attached to the lower edge of a corset and forming a loop to which the hose may be attached to maintain a yielding tension thereon in the various postures that the wearer may assume. A further object thereof is to produce a hose supporter attached at one end to the front of a corset and at the opposite end to the back thereof, having an intermediate sliding connection with a clip attached to the top of the hose whereby the supporter adjusts its position and relation to the hose attachment in the various postures of the body of the wearer. Another object of my invention is to produce a hose supporter comprising a flexible suspender, a portion of which is longitudinally adjustable and made of elastic material, one end of which is attached to the back of a corset and the opposite end being removably attachable to the front thereof, thus forming a loop having a swinging and sliding connection with the top of the hose to retain a tension thereon at all times; and a still further object of my invention is to produce a more simple, cheap, and efficient device of the character described than has heretofore been attained.

In the accompanying drawings, in which like reference characters indicate similar parts,

Figure 1 is a side view of my device in use;

Fig. 2 is a front view thereof; and

Fig. 3 is a detailed perspective of my invention detached.

Referring now to the drawings, 1 indicates a suspender comprising an adjustable elastic portion 2 attached to the back of a corset at 3. Said elastic portion is looped through the slotted plate 4 and secured in adjusted position by the buckle 5.

On the lower edge of the plate 4 is carried the swivel 6 to which one end of the non-elastic portion 7 of the suspender is at-

tached, while the opposite end is buttoned or otherwise removably attached to the front part of the corset at 8.

The non-elastic portion 7 is looped through the swivel 9 upon which the depending clip 10 is carried to be attached to the top of the hose.

As shown in the drawings, one of such supporters is attached to both sides of a corset and two of the same are attached to be carried between the legs of the wearer to support the hose on both sides, if desired. The pair of supporters attached to one of the hose may be held comfortably about the limb by the band 11 attached to the clips 10.

It will be appreciated from the foregoing description and by reference to the accompanying drawings, that the supporter thus described will maintain a constant tension on the hose in whatever position or posture the wearer assumes and will comfortably adjust its position by the sliding and swiveled relation between the parts thereof.

I claim:

1. A hose supporter, comprising a pair of looped suspenders attached at one end to the back of a body garment and removably attached at the opposite end to the front thereof, each of which includes an adjustable elastic portion at one end and a non-elastic portion at the opposite end, a depending swiveled clip slidably carried on the non-elastic portion for attachment to the hose of the wearer, one of said suspenders being carried between the legs of the wearer and the other on the side to maintain a constant and even tension on both sides of the hose, substantially as described.

2. A hose supporter comprising a pair of looped suspenders each of which is attached to the back of a body garment and removably attached at the opposite end to the front thereof, one of said suspenders being carried between the legs of the wearer and the other on the side, a clip slidably carried on each suspender for attachment to the hose and a band attached to both clips and surrounding the leg of the wearer, substantially as described.

In testimony whereof I affix my signature in the presence of two witnesses.

JAMES E. HANGER, JR.
